Filed Dec. 29, 1969, Ser. No. 20,668

Term of patent 14 years

Int. Cl. D12—16

U.S. Cl. D14—6

FIG. 1 is a top, side and front perspective view of a dune buggy display, showing my new design, the opposite side being substantially a mirror image thereof;

FIG. 2 is a fragmentary side elevational view of my dune buggy display along line 2—2 of FIG. 1;

FIG. 3 is a fragmentary front elevational view of my dune buggy display, along line 3—3 of FIG. 1; and

FIG. 4 is a fragmentary sectional view of my dune buggy display along line 4—4 of FIG. 2.

I claim:

The ornamental design for a dune buggy display, substantially as shown and described.
